Application December 6, 1943, Serial No. 513,020

13 Claims. (Cl. 66—89)

1

Our invention relates to improvements in hosiery knitting machines, particularly of the type for producing knitted fabric on a flat frame and shaping the fabric in the process of knitting.

The primary object of our invention is to form, during the process of knitting, a plurality of breather openings in the foot of the stocking or hosiery fabric made of nylon yarn or like plastic yarns.

A further object of our invention is to provide mechanism for locating these breather openings in areas and patterns in the foot of the stocking where they function to the best advantage.

A further object is to utilize the usual narrowing mechanism of the foot knitting machines and to provide said mechanism with modifications which render it capable of performing both the narrowing operations and the breather opening forming operations.

A further object is to provide attachments for the usual narrowing mechanism of foot knitting machines which enable said mechanism to perform the narrowing operations and the opening forming operations either simultaneously or independently during the knitting process, as required by the pattern and location of the breather openings in the foot area of the fabric.

A further object is to provide modifications of the narrowing mechanism for accomplishing the above results, which are readily adaptable to the normal operations of the narrowing mechanism and which are simple, easily installed and inexpensive.

Other objects will appear from the following description in connection with the accompanying drawings which illustrate one embodiment of our invention.

Referring to the accompanying drawings,

Fig. 1 is a diagrammatic view of substantially half the width of a flat knitted fabric forming the foot portion of a stocking, illustrating the pattern and location of the breather openings formed in the fabric, in accordance with our invention;

Fig. 2 is a front elevation of the upper left-hand portion of a full-fashioned knitting machine illustrating one of the knitting sections and the narrowing head and narrowing machine with which the invention is concerned;

Fig. 3 is a view similar to Fig. 2, illustrating another position of the narrowing head and narrowing machine parts;

Fig. 4 is another view similar to Fig. 2, but showing the narrowing head and narrowing machine parts in still another operating position;

2

Fig. 5 is a top plan view of the left-hand portion of the yarn carrier spindle mechanism and the narrowing head, with the parts shown in the operating position illustrated in Fig. 2;

Fig. 6 is an enlarged detail view, partly in section, substantially on the line 6—6 of Fig. 5;

Fig. 7 is an enlarged end view of the left-hand end of the mechanism shown in Figs. 2 to 5, illustrating the ratchet mechanism of the carrier

10 and the narrowing head;

Fig. 8 is a sectional view substantially on the line 8—8 of Fig. 6;

Fig. 9 is an enlarged detail plan section of one 15 of the narrowing nut guides and the cooperating stops on a wide finger narrowing rod;

Fig. 10 is an enlarged detail plan section of one 20 of the narrowing nut guides and the one-needle cam thereon, together with the cooperating stop on a narrow finger rod;

Fig. 11 is a detail section of the stop lock for 25 holding the narrow narrowing fingers in their central position behind the covering knife; and

Fig. 12 is an enlarged detailed elevation of the 30 needle bar 10, one of the wide fingers 12 and one 25 of the narrow fingers 13, as illustrated generally in Figs. 2, 3, and 4.

Referring more particularly to Fig. 1, the machine shown in the drawings is arranged to form 35 in the foot portion of a stocking a plurality of openings 1 larger than those in the normal mesh of the knitted fabric, through which the foot of the stocking may breathe while being worn to relieve the interior of moisture. It is desirable to form these breather openings during the process of knitting the fabric in a flat frame, and to 40 locate these openings close to the selvedges 2 of the fabric, so that when the selvedge edges are seamed together the breather openings will be on the under side of the foot. These open-

45 ings may be arranged in any suitable grouping or pattern and in sufficient number for the purpose. As indicated in Fig. 1, the openings are arranged in groups or patterns A and B beneath the instep of the foot and the toe of the foot. It is understood, of course, that in Fig. 1 only one-half of the width of the flat fabric is shown, and that similar patterns are formed adjacent the opposite selvedge margin of the fabric. This means that in fact there are two groups A formed

50 in the fabric, which will be located beneath the instep, one on each side of the center seam. Likewise two groups B of openings will be located beneath the toe portions, one on each side of the center seam. The openings in the groups A are disposed in narrow elongated patterns the mar-

gins of which for a portion of their length are parallel with and close to the selvedges 2, and the rows or courses of openings are spaced apart lengthwise of the fabric by a plurality of plain knitted courses. The arrangement is such, therefore, that the rows are all formed a definite distance in from the selvedges of the fabric. The openings in groups B are likewise arranged in courses equidistant inwardly from the selvedge margins, but in this pattern the courses of openings are spaced apart lengthwise of the fabric by one plain-knitted course, so that the openings are more closely grouped than those in pattern A.

In accordance with this preferred arrangement or patterning of the openings, a part of the pattern A lies in the narrowed portion of the fabric beneath the instep, and the other part of the pattern lies within the plain knitted portion of the fabric. The pattern B, however, lies entirely within the narrowed toe portion of the fabric. For the purposes of description, therefore, we have designated these several portions of the fabric as zones C, D, E, F and G, since the mechanism functions differently in certain respects in the several zones.

We utilize the narrowing head and the narrowing machine of a full-fashioned footer knitting machine for the purpose of narrowing the fabric and forming the openings 1 therein, but we have modified these mechanisms so that the openings will be located in the proper place in the fabric, irrespective of whether the openings are formed simultaneously with narrowing operations or independently thereof. In other words, the openings of pattern A in zone C and of pattern B in zone F are formed simultaneously with the narrowing of the fabric, whereas the openings in pattern A within the zone D are formed in the fabric without the narrowing of the fabric.

The structure and operation of the knitting machine itself, and of the narrowing head and narrowing machine used in the production and fashioning or shaping of the foot portion of the stocking, are well known and understood. We have, therefore, illustrated only those parts of these mechanisms which are necessary to an understanding of the invention. For this reason, the knitting machine itself is represented only by the needle bar 10 (Figs. 2, 3 and 4) of one section of a multi-section machine, so that the relative positions of the wide and narrow fingers can be explained.

The narrowing machine which carries the narrowing fingers functions to take the loops from the needles and transfer them to adjacent needles. In a footer, the narrowing machine has four fingers for each section, two wide fingers 12 and two narrow fingers 13, both of which are provided with narrowing points. However, in the present machine we substitute lace points in the narrow fingers for the production of the breather openings 1 in the fabric. The lace points, as is well understood, are spaced to engage alternate knitting needles and to displace the loops a distance of one needle. Since there is no loop to replace the ones taken off, openings are formed in the fabric at that place.

The fingers are carried by the narrowing rods 14 and 15 respectively, which slide longitudinally in bearing brackets 16 distributed along the length of the machine to shift the fingers toward and from the center of the fabric from each side thereof. These rods and bearing bracket

ets form part of an assembly which bodily moves vertically to bring the finger points into and out of engagement with the knitting needles for the purpose of taking the loops from the needles and transferring them again to adjacent needles. The cam mechanism for imparting vertical movement to the narrowing rod assembly, and the chain motion for automatically bringing the narrowing machine into and out of operation, are well known and understood and are therefore not shown.

The longitudinal movement of the narrowing rods, for the purpose of shifting the narrowing fingers laterally to diminish the width of the fabric is brought about through the action of the narrowing head. The narrowing head consists generally of the narrowing nuts 20 and 21, and the narrowing spindle 22 which is mounted in suitable bearings 23 (Fig. 5) on the frame. The nuts are moved along the spindle by means of the threads 24, half of which are left-handed and the other half right-handed, so that on the rotation of the spindle the nuts travel toward or from each other. These nuts have forked extensions 25 and 26 which embrace a guide shaft 27 to guide the nuts and hold them against rotation on the spindle. The narrowing nuts actuate the narrowing rods and for this purpose have guide pieces 28 and 29 which extend upward adjacent the narrowing rods and are adapted to engage end stops on the narrowing rods. The narrowing nut guide pieces are elongated so that the narrowing rod end stops can slide on the faces of the guide pieces when the narrowing machine assembly is moved vertically. In the usual narrowing machine, the wide finger rods 14 are provided with single stops 30 and 31 (Figs. 9 and 10) which are maintained against the faces of the guide pieces by springs. In the present machine, however, the wide finger rods are provided with additional stops 32 and 33 which bear against the opposite faces of the guide pieces 28 and 29 so that movement is imparted positively to the rods in both directions of movement of the narrowing nuts. These additional stops are provided for the reason that, as will hereinafter appear, the narrow finger rods 15 are, during certain operations of mechanism, locked to the wide finger rods 14 and the additional load thereby imposed upon the wide finger rods 14 makes it advisable to have the narrowing nuts positively move the narrowing rods in either direction. The narrow finger rods 15 likewise have stops 34 and 35 which bear against cam pieces 36 on the inner faces of the guides 28 and 29. These cam pieces have beveled faces 37 which cause the narrow fingers to be shifted toward the center of the fabric a distance equal to one needle during that portion of the narrowing operation indicated as zone F, as will hereinafter appear.

The narrowing head includes pawl and ratchet mechanism (Figs. 6, 7 and 8) associated with the outer end of the spindle for rotating the spindle. The spindle is also provided with a hand crank 38 by which it may be rotated in either direction to move the narrowing nuts and shift the fingers to position the fingers relatively to the fabric. The pawl and ratchet mechanism consists of two ratchets 40 and 41, and two pawls 42 and 43, both of which are actuated by the fork member 44. The teeth of the ratchet 40 are engaged by the pawl 42 during the upward stroke of the fork 44 to rotate the spindle in right-handed direction, while the teeth of the ratchet 41 are en-

gaged by the pawl 43 upon the downward stroke of the fork 44 to rotate the spindle in the reverse or left-handed direction. The teeth of the ratchet 40 are so spaced that the upward stroke of the fork will rotate the spindle a distance of two teeth, and this rotation is sufficient to move the narrowing nuts and consequently the wide fingers a distance of two needles. Normally, in the formation of the diamond point toe portion of the foot, the wide and narrow fingers are spaced apart one-needle distance, as indicated in Fig. 2, so that the two-needle movement of the wide fingers first closes up the space between the wide fingers and the narrow fingers, and then moves the narrow fingers a distance of one needle. After the narrowing machine assembly has dipped downwardly, transferred the loops to the adjacent needles and rises again to inactive position, the spindle shaft is given a reverse rotation equivalent to one needle distance by the pawl 43 acting on the ratchet 41 on the downstroke of the fork 44, thus restoring the one-needle space between the wide and narrow fingers. In the present structure we utilize this two-needle inward, one needle reverse movement of the wide and narrow fingers in the formation of the gusset narrowing portion of the foot and in the formation of the openings 1 in zone C of the fabric. An index wheel 45 is mounted on the spindle shaft between the two ratches 40 and 41, and has a series of notches 46 which are engaged by a plunger 47 to hold the spindle in its rotated position. The notches on this index wheel are spaced apart a distance corresponding to one-needle movement of the fingers.

The fork 44 also operates the carrier rod nut 50 (Figs. 5 and 7) which, as is well known, shortens the travel of the yarn carrier rods coincident with the movement of the narrowing fingers which determine the width of the fabric. The carrier nut is mounted to travel on the threaded carrier spindle 51 which has a ratchet 52 adapted to be engaged by a pawl 53 to correspondingly move the carrier rod nut, the pawl 53 being actuated on the upstroke of the fork 44. When this pawl is disengaged from ratchet 52, the carrier rods and hence the yarn carriers are not moved during non-narrowing operations. The carrier mechanism needs no further description, except so far as the movement of the carrier rod nut controls the position of the pawl 43 with respect to its engagement or non-engagement with the ratchet 41. The carrier rod nut has a forked extension 54 which embraces and is guided by the guide shaft 55. The forked extension has an upstanding portion 56 which in its travel engages a cam piece 57 on a rocker bar 58. The rocker bar is journaled on the shaft 55 and has a downwardly extending member 59 forming a lever which is attached to the rod 59 mounted in bearings 60. The rod has a pin 61 on a collar which engages the pawl 43 to throw the pawl out of engagement with the ratchet 41. Thus, when the member 56 engages the cam piece 57 and swings the lever 59 to the left (Fig. 7), it disengages the pawl 43 from the ratchet 41. When the cam piece 57 rides off of the member 56, the rod moves to the right under the action of spring 62 and allows the pawl to be brought into engagement with the ratchet 41 by the spring 63. When the pawl 43 is out of engagement with the ratchet 41, the narrowing nut spindle is not rotated reversely on the downstroke of the fork, hence the wide fingers are not moved outwardly one-needle distance after their two-needle advance inwardly,

5

as previously explained. The cam piece 57, therefore, is placed on the rocker bar 58 in the position in which it will be engaged by the member 56 when the narrowing operation is to begin in the zone F.

10 In accordance with our invention, we provide means for controlling the action of the pawl 42 and ratchet 40 on the narrowing nut spindle, so that the formation of the breather openings can continue in the zone D without narrowing the fabric.

15 A cam 70 is mounted on the narrowing spindle 22 (Figs. 6, 7 and 8) immediately adjacent the ratchet 40. The high portion 71 of this cam projects beyond the ratchet teeth and is arranged to throw the pawl 42 out of engagement with the tooth and causes it to skip the immediate tooth and engage the next tooth on its upward stroke. In this way, the pawl operates to rotate the spindle and move the wide fingers one-needle distance instead of two; but this occurs when the narrowing nuts and the wide fingers are in their extreme outward position, as shown in Fig. 3, and the wide fingers are out of the field of the fabric so that they do not narrow the fabric. The cam is connected by the links 72 to the arm 73 of a bell crank pivoted at 74 in a bracket 75 on the frame. The other arm 76 of the bell crank has an adjustable stop 77 which is positioned in the path of 20 the extension 25 of the left-hand narrowing nut 20. These parts are so proportioned and arranged that when the narrowing nut 20 is in its extreme outward position, as shown in dotted lines in Fig. 6, it will have actuated the bell crank lever to 25 the position indicated in dotted lines and rotated the cam 70 into position to cause the pawl 42 to skip one tooth on the ratchet. Thus when the pawl 42 skips a tooth and rotates the spindle, it moves the narrowing nut 20 only one-needle distance away from its extreme position and allows the spring 78 to restore the bell crank and move the cam 70 away from its pawl-engaging position. On the downstroke of the fork, however, the pawl 43 imparts a reverse rotation to the spindle and 30 moves the nut 20 outwardly again the equivalent of one-needle distance, and again throws the cam 70 in position to engage the pawl 42 and cause it to skip a tooth. Thus the narrowing nut 20 moves inwardly on the spindle one-needle distance and back again one-needle distance each time the narrowing head operates. This is for 35 the purpose of maintaining the wide fingers 12 in their extreme outer position out of the knitting field, as shown in Fig. 3, so that during that 40 portion of the operation indicated in zone D the fabric will not be narrowed but the narrow fingers will function to form the breather openings 1 in that zone.

45 Since it is necessary in the formation of openings 1 in the zone D to maintain the narrow fingers in the same spaced relation to the selvedge, we provide means for locking the wide and narrow fingers in that relation. This locking means consists of latch hooks 80 which are pivotally mounted at one end 81 on the wide finger and narrow finger rods 14 and 15. The other ends 82 are formed as hooks to engage studs 83 on the narrowing rods 14 and 15. Thus when these hooks are engaged with the studs 83, they lock the narrowing rods 14 and 15 together so that the one-needle movement each way imparted to the wide finger narrowing rods 14 will likewise be transmitted to the narrow finger narrowing rods 15. These latch hooks are made adjustable 50 in length so that the spacing between the wide

and narrow fingers can be adjusted very accurately.

The usual narrowing mechanism of a footer knitting machine includes a covering plate and a covering motion located in the center of the knitting section and adapted to gradually eliminate the points of the narrow fingers from the knitting field in the formation of so-called diamond point toe. As the narrow fingers reach the end portion of the toe, the covering plate enters between the narrowing points and the needles to prevent the narrowing points from picking up and transferring the loops to adjacent needles. Since we do not form a diamond point toe in the foot portion of the stocking, we utilize the covering plate for preventing the formation of openings 1 by the lace points in the narrow fingers during the knitting of the fabric in zone C.

Since the function of the covering plate and the mechanism for operating it in proper timed relation to the narrowing operation is well known and understood, we have deemed it unnecessary to illustrate this mechanism except to show the covering plate 85 itself carried on the shaft 86. We utilize this covering plate for eliminating the narrow finger points during the process of continuing the narrowing of the toe in the zone G after the pattern B of openings terminates. In order to eliminate these narrow fingers during the narrowing operation in zone G, the narrow fingers are shifted to the center of the knitting field behind the covering plate 85, as shown in Fig. 4. This is done by shifting the narrow finger rods 15 by hand until the narrowing fingers are together behind the covering plate. In order to hold these fingers in this position against accidental displacement by vibration or otherwise, there is provided a stop lock for each of the two narrow finger rods 15. These stop locks are located at the end of the machine and consist of spring latches 88 mounted on the narrowing rod bearing 16 and adapted to snap over blocks 89 fastened to the rods 15 in a position corresponding to the position of the narrowing fingers behind the covering plate.

The operation of the mechanism is as follows:

When the plain knitting of the fabric reaches the zone C and it is desired to narrow the fabric and form the breather openings 1 simultaneously, the machine is stopped and the parts adjusted to the position shown in Fig. 2. This is done by rotating the spindle by hand to shift both the wide fingers 12 and the narrow fingers 13 into proper position with respect to the selvedges of the fabric. The wide and narrow fingers are one-needle apart. The machine is again started with the narrowing mechanism in operation under the control of the chain motion until the end of the zone C is reached. During this operation the fabric is narrowed and the openings 1 are simultaneously formed. The wide finger points dip downwardly, pick up the selvedge loops, shift inwardly a two-needle distance and move the narrow fingers one-needle distance, dip downwardly again to transfer the loops to the needles and rise again to inactive position, ready for the next cycle of operation. During the rise to inactive position, the ratchet 41 and pawl 43 reverse the movement of the wide fingers one-needle distance outwardly to restore the one-needle space between the wide and narrow fingers. During this narrowing cycle, the points in the narrow fingers form the openings 1. Since this operation employs the two-needle inward, one needle reverse movement of the narrowing mechanism,

each course of openings 1 in zone C is formed one needle distance closer to the selvedge margin of the fabric; hence in starting zone C, the narrow fingers are positioned sufficiently inwardly from the selvedge to cause the last course in zone C to be formed at the desired distance from the selvedge margin.

When the end of zone C is reached, the formation of the openings 1 is continued in the zone D but without narrowing the fabric. At the end, therefore, of zone C, the machine is stopped and the parts are adjusted for the operations in zone D. This position of the parts is shown in Fig. 3. The narrow fingers remain in their same position but the wide fingers are adjusted to their extreme outward position out of the knitting field by rotating the spindle by the hand crank 38. This adjustment brings the narrowing nuts 20 and 21 to their extreme outward positions and causes the nut 20 to engage the stop 17 on the bell crank 18 and rotate the cam 19 to disengage the pawl 42 and cause it to skip a tooth on the ratchet 40 when the pawl is actuated on the upstroke of the fork 44. Thus the wide fingers will be given an inward movement of only one-needle distance instead of two, and upon the downstroke of the fork, when the narrowing mechanism rises to inactive position, will be given a reverse movement of one-needle distance by the pawl 43. The narrowing rods 14 and 15 are now locked together by these latches 80 so that this one-needle movement each way of the wide fingers will be imparted to the narrow fingers. The machine is now started and the narrowing mechanism will dip the narrowing fingers 13 downwardly to pick up the loops, shift the points one-needle distance to displace the loops and form the holes, dip again to transfer the loops to the adjacent needle and rise again to inactive position. Upon rising to inactive position, the ratchet mechanism moves the narrow fingers outwardly again one-needle distance ready for the next cycle of operation. Thus the narrow fingers will, in each operation, form the openings 1 in the same wales of the fabric and maintain the courses of openings the same distance from the selvedges throughout the zone D. When the machine is stopped for adjustment of the parts at the beginning of zone D, the pawl 53 is thrown by hand out of engagement with the ratchet 52, so that on the upward stroke of the yoke 44 the carrier rod nut 50 and hence the yarn carriers will not be moved inwardly; hence the width of the fabric remains uniform during the operations in zone D.

Upon the termination of the pattern of openings 1 at the end of zone D, the conventional chain control of the narrowing mechanism automatically renders this mechanism inactive and the knitting machine continues the plain knitting of the fabric until the zone F is reached, whereupon the machine is stopped and the parts adjusted to narrow the foot portion of the fabric and simultaneously form the openings in pattern B.

To adjust the parts for these operations, the pawl 53 is thrown into engagement with the ratchet 52, the narrowing rods are unlocked by the disconnection of latches 80 and the spindle rotated to position the wide fingers one-needle distance from the narrow fingers, as shown in Fig. 2. At this time the carrier nut will be in the position (Fig. 5) in which the member 65 is about to ride the cam piece 56 and swing the pawl 43 away from its ratchet 41 so that the narrowing spindle will not be reversely rotated. Upon start-

ing the machine, the wide fingers will dip, pick up the selvedge loops, shift inwardly a two-needle distance, dip again to transfer the loops and rise to inactive position ready for the next cycle. Likewise, the narrow fingers will displace the loops to form the openings 1. During this operation, the wide fingers will not be given a reverse or outward movement of one-needle distance because the pawl 43 is out of engaging position with respect to cam 41. Instead, the narrow fingers will be moved further inwardly a one-needle distance by the cam pieces 36 on the narrowing nut guides 28 and 29 as the narrowing frame rises to inactive position, thus restoring the one-needle spacing of the wide and narrow fingers. The simultaneous narrowing operation and the formation of the openings in pattern B will continue to the end of zone F.

It is now desired to continue the narrowing of the toe portion in the zone G without the formation of the openings 1. By this time, the member 65 will have ridden off the cam piece 56 and restored the pawl 43 to engaging position with the ratchet 41. The machine is stopped and the parts adjusted to prevent the narrow finger points from forming the openings. This adjustment is made by shifting the narrowing rods 15 and the narrow fingers 13 toward the center of the fabric to a position behind the cover plate 85, as shown in Fig. 4. The wide fingers are then adjusted by rotating the spindle by hand until the wide fingers are in position, as shown in Fig. 4, to engage and transfer as many of the selvedge loops as desired. After this adjustment, the machine is then started and the wide fingers will dip, pick up the loops, shift a two-needle distance inwardly, dip again to transfer the loops and rise to inactive position ready for the next cycle. During the rise to inactive position, the wide fingers will be given a reverse outward movement of one-needle distance because both pawls 42 and 43 are in position to engage their respective ratchets normally.

We claim:

1. In a full-fashioned foot knitting machine having a narrowing machine including wide fingers and narrow fingers, and a narrowing head including means for actuating said wide fingers to narrow the fabric, means to lock the narrow fingers to said wide finger actuating mechanism, with the wide fingers out of the knitting field, and means operable when said narrow fingers are locked to said actuating mechanism to cause said actuating mechanism to move the narrow fingers inwardly one needle distance and outwardly one needle distance with respect to the selvedge margin of the fabric.

2. In a full-fashioned foot knitting machine having a narrowing machine including wide fingers and narrow fingers, and a narrowing head including means for actuating said wide fingers to narrow the fabric, means to lock the narrow fingers to said wide finger actuating mechanism, with the wide fingers out of the knitting field, and means for causing said wide finger actuating mechanism to advance one-needle distance and to retreat one-needle distance.

3. In a full-fashioned foot knitting machine having a narrowing machine including wide fingers and narrow fingers, and a narrowing head including means for actuating said wide fingers to narrow the fabric, means to lock the narrow fingers to said wide finger actuating mechanism with the wide fingers out of the knitting field, and means for advancing and retracting said wide

and narrow fingers alternately one-needle distance with respect to the fabric being knitted.

4. In a full-fashioned foot knitting machine having a fabric narrowing mechanism, including wide and narrow fingers and narrowing rods therefor, the combination of a narrowing head acting on said wide finger narrowing rods for advancing the fingers progressively toward the center of the fabric, means for neutralizing each advance of the wide fingers, and means for locking the wide and narrow finger narrowing rods together to impart to said narrow fingers the advance and neutralizing movement of the wide fingers.

5. In a full-fashioned foot knitting machine, the combination of a narrowing mechanism including wide fingers having narrowing points and narrow fingers having lace points, means for advancing the wide fingers two needle distance and retracting the wide fingers one needle distance with respect to the fabric being knitted, means for positioning the wide fingers out of the knitting field of the fabric to prevent the narrowing operation of said wide fingers, means for connecting the narrow fingers to said wide finger advancing and retracting means, and means to change the operation of said advancing and retracting means to a one needle advance one needle retreat.

6. In a full-fashioned foot knitting machine, the combination of wide and narrow fingers, narrowing rods therefor, a spindle, narrowing nuts on the spindle for actuating said narrowing rods, pawl and ratchet mechanism for rotating the spindle in both directions with respect to the fabric, means for positioning the wide fingers only out of the knitting field of the fabric, and means for causing said pawl and ratchet mechanism to rotate said spindle equal distances in both directions when the wide fingers are out of the knitting field whereby equal inward and outward movements are imparted to the narrow fingers which lie within the knitting field.

7. In a full-fashioned foot knitting machine having narrowing mechanism including wide fingers and narrow fingers and narrowing rods therefor, a narrowing head including a narrowing spindle and ratchet means for advancing the wide fingers a two-needle distance and retracting the wide fingers a one-needle distance, a cam associated with said ratchet mechanism for reducing the advance of wide fingers to a one-needle distance, and means operable when the wide fingers are in their extreme outward position for rendering said reducing means operable.

8. In a full-fashioned knitting machine, the combination of a narrowing machine including wide fingers and narrow loop displacing fingers and narrowing rods carrying said fingers, a narrowing head mechanism including a narrowing spindle, narrowing nuts on said spindle for actuating said rods and a ratchet mechanism for rotating said spindle in either direction, including pawls acting on said ratchets, a cam associated with said ratchet mechanism and acting on one of the pawls for limiting the rotation of the spindle in one direction, and means operable by one of said narrowing nuts in a given position for rendering said cam operable.

9. An attachment for the narrowing mechanism of a full-fashioned knitting machine, comprising a cam on the spindle of the narrowing head adjacent the ratchet and adapted when operated to engage the pawl and cause it to skip a tooth on the ratchet, and means operable by one

of the narrowing nuts in its extreme outward position on the spindle for operating said cam.

10. An attachment for the narrowing mechanism of a full-fashioned knitting machine having wide and narrow fingers and narrowing rods therefor, comprising a cam on the spindle of the narrowing head adjacent the ratchet and adapted when operated to engage the pawl and cause it to skip a tooth on the ratchet, means operable by one of the narrowing nuts in its extreme outward position on the spindle for operating said cam, and means for interlocking the wide and narrow finger narrowing rods with the wide fingers in their outward position out of the knitting field and the narrow fingers in position to displace loops in the fabric in a given relation to the selvedges.

11. An attachment for the narrowing mechanism of a full-fashioned knitting machine having wide and narrow fingers and narrowing rods therefor, comprising a cam on the spindle of the narrowing head adjacent the ratchet and adapted when operated to engage the pawl and cause it to skip a tooth on the ratchet, means operable by one of the narrowing nuts in its extreme outward position on the spindle for operating said cam, and latch members on the narrowing rods for locking the wide and narrow finger rods together with the wide fingers in their extreme outward position out of the knitting field and with the narrow fingers in position to displace the loops in the fabric adjacent the selvedges thereof.

12. In an attachment for a narrowing mechanism of full-fashioned flat fabric knitting machines of the type having wide and narrow fingers and in which the narrowing spindle is rotated by pawl and ratchet mechanism the equivalent of a two-needle distance movement of the wide fingers in one direction and a one-needle distance movement in the reverse direction, the combination of a cam on the spindle adjacent the ratchet adapted when rotated to disengage the pawl from the ratchet and cause it to rotate the spindle the equivalent of one-needle distance movement of the wide fingers, and means connected with said cam and positioned to be en-

gaged by one of the narrowing nuts on the spindle when said nut is in its extreme outward position to operate said cam.

13. In an attachment for a narrowing mechanism of full-fashioned flat fabric knitting machines having wide and narrow fingers and narrowing rods therefor and in which the narrowing spindle is rotated by pawl and ratchet mechanism the equivalent of a two-needle distance movement of the wide fingers in one direction and a one-needle distance movement in the reverse direction, the combination of a cam on the spindle adjacent the ratchet adapted when rotated to disengage the pawl from the ratchet and cause it to rotate the spindle the equivalent of one-needle distance movement of the wide fingers, a bell crank connected with said cam and positioned to be engaged by one of the narrowing nuts on the spindle when said nut is in its extreme outward position to operate said cam, and latch means for locking together the wide and narrow finger narrowing rods with the wide fingers in the extreme outward position and the narrow fingers in position to displace loops at a given distance from the selvedges of the fabric.
